TOY CAP PISTOL

Willard R. Bixler, Kenton, Ohio

Application September 22, 1930, Serial No. 483,667
Renewed November 2, 1932

8 Claims. (Cl. 124—14)

This invention relates generally to the class of toys, and broadly aims to provide an improved toy cap pistol which includes means for holding under tension thereon and projecting therefrom an elastic band, upon movement of the hammer to fire a cap, whereby to simulate the coincidental projection of a projectile, thus adding materially to the amusement afforded by the use of the pistol.

10 The specific object of the invention comprises the provision of a fluted or channeled detent, for instance one of cross-sectional T-shape, with a guiding opening in a part of the pistol structure, said opening having a contour in agreement with 15 the cross-sectional shape of the detent thereby providing shoulders which facilitate the stripping of the bight of an elastic element supported across outstanding ridges of the detent.

With the above recited and other objects in view, reference is had to the following description and accompanying drawing, in which there is exhibited one example or embodiment of the invention, while the claims define the actual scope of the same.

25 In the drawing:

Figure 1 is a plan view of a toy cap pistol equipped with an elastic band holding and projecting means and disclosing the parts in set position with the band in place.

30 Figure 2 is a side view thereof.

Figure 3 is a fragmentary enlarged inner side view of the mechanism containing section of the pistol.

Figure 4 is a view similar to Figure 3, illustrating the actuated position of the parts.

Figure 5 is a fragmentary sectional plan view taken approximately on the line indicated at 5—5 in Figure 4.

Figure 6 is a detail plan view particularly illustrating the shoulders which, in fitting the flutes or channels of the cross-sectional T-shape of the detent, facilitates stripping the bight of the elastic element from the detent.

Referring to the drawing by characters of reference, A and B designate generally the mating sections of the pistol which are secured together in the usual manner by a pair of rivets C. The sections A and B are of similar construction, each including the mating barrel simulating portions 10, cylinder simulating portions 11, stock simulating portions 12 and cap seat defining portions 13. The section A, which acts as a container for the trigger and hammer mechanism, is provided with a trigger guard 14 and has mounted on an inwardly projecting integral trunnion 15 for

swinging movement, a piece 16, the upper extremity 17 of which constitutes the hammer and the lower projecting extremity 18 of which constitutes the trigger. The usual form of leaf spring 19 is contained within the stock portion 60 12 of the section A and coacts with the notch 20 in the piece 16 to effect the movement and forcible contact of the hammer extremity 17 with the cap receiving seat portions 13 when the hammer extremity 17 is cocked and the trigger extremity 65 18 is pulled.

In order to provide means for holding the elastic band D stretched and under tension approximately in longitudinal alignment with the barrel simulating portions 10, the forward or muzzle end 70 thereof is notched as at 21 and a vertically movable detent arm 22 projects upwardly from the upper surface of the rear portion of the barrel simulating sections 10. The detent element 22 is operatively connected with a forwardly projecting 75 lug 23 on the piece 16 and is designed to be disposed in an upwardly projecting position when the piece 16 is in its set position, illustrated in Figure 3, where the hammer extremity 17 is cocked and the trigger extremity 18 is disposed 80 forwardly. The detent element 22 is designed to be retracted flush with or below the upper surface of the barrel when the piece 16 is swung to the position illustrated in Figure 4 under the action of the spring 19 when the trigger is pulled. 85 In practice, the detent will preferably be of substantially T-shaped formation in cross section, as clearly illustrated in Figures 1 and 5, and the mating edges of the sections A and B will be notched to provide a correspondingly T-shaped 90 opening 24, although it is to be clearly understood that within the scope of the invention, the cross sectional shape of the detent 22 and its opening may be varied. In order to avoid the necessity of employing a rivet, bolt or analogous 95 means for operatively connecting the detent element with the lug 23, the said lug is preferably provided with a laterally projecting integral pintle or stud 25, while the lower end of the detent element is formed with a receiving aperture 26, 100 the said lower apertured end of said detent being maintained over the pintle or stud 25 by an inclined integral rib 27 cast on the inner side of the section B and extending throughout the path of movement of the apertured lower portion of the detent element. While it has been previously set forth that the detent 22 and the opening 24 are not necessarily restricted to a T-shaped cross sectional configuration, and the invention is not necessarily bound to this shape, an advantage is 105 110

derived therefrom due to the fact that shoulders 28 (Fig. 6) are provided which intersect the path of movement of the portions 29 of the elastic band D which are stretched over the re-entrant angles formed by the opposite sides of the stem 30 and the under side of the head 31 of the T-shaped construction. This makes for a more positive release or displacement of the band from the detent element 22 when the same is retracted 10 below the upper surface of the barrel.

It will be understood from the foregoing taken in connection with Figure 6, that the stem 30 of the detent, which is disposed rearwardly of the head 31, combines with the head to form re-entrant angles 32. Since the contour of the opening 24 in the pistol structure agrees with the cross-sectional shape of the detent it follows that the shoulders 28 in the pistol structure will be in the way of the elastic portions 29 when these 20 portions are carried down with the detent.

So, as has been said, the shoulders 28 intersect the path of movement of the portions 29 and provide rather extensive abutments which insure the stripping of the bight of the elastic element from 25 the detent. It is to be noted that the outstanding ridges 33, 34 respectively of the head 31 and stem 30, reduce the points of contact of the elastic element to a minimum. The contactable expanse of the shoulders 28 far exceeds the contacting 30 areas at the points 33, 34 with the result that the bight of the elastic element is stripped off of the detent without any possibility of the element being crowded into the opening 24 by virtue of its tenacious hold on the detent.

35 In use and operation, the hammer is moved to the cocked position illustrated in Figures 1, 2 and 3. The movement of the hammer projects the detent element 22 upwardly, so that its upper end protrudes above the upper surface of the barrel. The elastic band D is then stretched under tension over the notched forward or muzzle end 21 of the barrel and the protruding portion 40 of the detent, as clearly disclosed in Figures 1, 2 and 3. The cap E may be inserted in the cap receiving portion 13 and when the trigger 18 is 45 pulled, the spring 19 functions to swing the hammer 17 forwardly into forcible contact with the cap E. Simultaneously the upper exposed end 50 of the detent member 22 is retracted flush with or below the upper surface of the rear portion of the barrel to release the rear end of the elastic band D and permit the projection of the band forwardly under its inherent elastic action. The user thereby is afforded the additional amusement 55 of observing the simulated shooting of a projectile coincident with the firing of the cap.

From the foregoing, it will thus be seen that an improved toy cap pistol has been devised, by virtue of which elastic bands may be held under tension thereon and released coincident with the movement of the hammer to a firing position. While there have been illustrated and described certain details of construction, no limitation is necessarily made thereto except as defined by the 65 appended claims.

What is claimed is:

1. In a toy pistol including a cylinder and pivoted spring-actuated trigger-hammer piece; means for detaining the bight of an elastic element while said piece is cocked, comprising a fluted detent, and means pivotally connecting the end of the detent to said piece, said cylinder having an opening outlining a re-entrant angle to cross-sectionally match the detent, said angle 70 providing a shoulder to fit the flute and facilitate

stripping the bight of the elastic element from the detent.

2. In a toy pistol including a cylinder and pivoted spring-actuated trigger-hammer piece; means for detaining the bight of an elastic element while said piece is cocked, comprising a cross-sectionally T-shaped detent, and means pivotally connecting one end of the detent to said piece, said cylinder having an opening outlining re-entrant angles to cross-sectionally match the detent, said angles providing shoulders to fit the T and facilitate stripping the bight of the elastic element from the detent. 80 85

3. In a toy pistol having barrel and handle portions, a cap holding anvil, a trigger member movably mounted within said pistol and having a finger portion of said trigger member extending below said barrel portion and having a hammer member extending above said barrel to cooperate with said anvil to fire a cap in said anvil, the improvements comprising a rubber band detent member mounted within said piston and in engagement with said trigger member and adapted to be moved to have a part of itself extend outside of said pistol to receive a rubber band when said trigger element is cocked, said detent member including two or more transversely spaced points for receiving the rubber band and assuring non-engagement of said detent with the band between said points, the barrel portion through which 100 said detent member extends being formed to contact the rubber band between the points of engagement on said detent member when said detent member is being drawn into the barrel to thereby assist in stripping the band from said 105 detent member. 90 95

4. In a toy pistol having barrel and handle portions, a cap holding anvil, a trigger member movably mounted within said pistol and having a finger portion of said trigger member extending below said barrel portion and having a hammer member extending above said barrel to cooperate with said anvil to fire a cap in said anvil, the improvements comprising a rubber band detent member mounted within said pistol and in engagement with said trigger member and adapted to be moved to have a part of itself extend outside of said pistol to receive a rubber band when said trigger element is cocked, said detent member including two or more transversely spaced 110 points for receiving the rubber band and assuring non-engagement of said detent with the band between said points, the barrel portion through which said detent member extends being formed to contact the rubber band between the points of engagement on said detent member when said 115 detent member is being drawn into the barrel to thereby assist in stripping the band from said detent member. 120 125

5. In a toy pistol including a cylinder and pivoted spring-actuated trigger-hammer action piece; the improved means for detaining the bight of an elastic element while said piece is cocked comprising a fluted detent, said detent comprising a rubber band retaining portion disposed rearwardly of said detent member and a forwardly disposed spreader portion, the detent member thus forming a three-point support for the rubber band with a minimal contact area, means pivotally connecting the end of the de- 130 135 140 145 150

tent to the trigger hammer piece, said cylinder having an opening outlining reentrant angles to conform to the detent and form shoulders to fit the flutes and form platforms to facilitate stripping the bight of the elastic element from the detent.

6. In a toy pistol including a cylinder, a combination detent and pivoted spring-actuated trigger-hammer action piece, the improved means 10 for stripping an elastic element from the detent comprising lateral recesses formed in the rear aspect or face of the detent providing a three-point support for the bight of an elastic element and means on the cylinder of the pistol positioned in the intervening spaces between the 15 points of support to prevent the elastic element from being drawn into the cylinder upon retraction of the detent.

7. In a toy pistol of the type described, an improved 20 detent member adapted to detain the bight of an elastic element while permitting a rapid release of same with a minimum of frictional resistance comprising a T-shaped detent member forming a three-point support for the bight of

an elastic element, the detent being so disposed as to provide a single point of contact for the bight at its rearmost portion and to spread the bight apart at the foremost portion of the detent, thereby providing areas between the detent member and the legs of the bight formed between the three supporting points, the said detent being incorporated in the cylinder of the pistol having shoulders conformed to the cross section of the detent, the said shoulders providing stripping platforms adapted to receive and support the spaced, free portions of the bight of the elastic element and prevent same from being withdrawn with the detent into the cylinder of the pistol.

8. A detent member for toy pistols adapted to 80 discharge elastic elements comprising a member having a T-shaped cross-section and forming a combined holder and spacer for the bight of an elastic element, the said elastic element being supported by said detent at three points, providing a minimum frictional support and detaining area for the bight of the said elastic element.
